UNITED STATES PATENT OFFICE.

CHARLES A. BACKSTROM, OF TRENTON, NEW JERSEY.

CENTRIFUGAL LIQUID-SEPARATOR.

SPECIFICATION forming part of Letters Patent No. 355,247, dated December 28, 1886.

Application filed June 15, 1886. Serial No. 205,288. (No model.)

To all whom it may concern:

Be it known that I, CHARLES A. BACKSTROM, a citizen of the United States, residing at Trenton, in the county of Mercer and State of New Jersey, have invented certain new and useful Improvements in Centrifugal Liquid-Separators, of which the following is a specification, reference being had therein to the accompanying drawings.

- 10 This invention has relation to centrifugal machines, and although described herein in connection with a use thereof for the purpose of separating cream from milk, the invention is, however, capable of embodiment in centrifugal machines to be used for the purpose of separating liquids of different specific gravities from each other and in all arts involving the necessity of a separation of liquids or liquids and solids.
- 15 Other objects of the invention, as well as its construction and operation, will be hereinafter described, and the novel features thereof particularly pointed out in the claims.

Referring to the drawings, Figure 1 is a central vertical section of a centrifugal machine constructed in accordance with my invention. Fig. 2 is a perspective of that portion of the machine which receives and delivers the separated liquids. Fig. 3 is a sectional view of a modification hereinafter described, and Fig. 4 is a horizontal section of the separating-vessel proper, said section being taken on the line X of Fig. 1.

Like letters indicate like parts in all the figures of the drawings.

A represents the stand or frame-work of the machine; and it consists of a single casting having openings A' A² A³ leading into the several compartments formed by two bridges, A⁴, which are cast as a part of the stand A. Within each of the bridges A⁴, or it may be formed as a part thereof, is a pocket, B, which serves to receive a shell, C, which is one of several parts constituting the bearing for the driving-spindle D. Within each of the shells C is arranged a lining, E, which, as usual in high-speed spindle-bearings, is adapted, by means of perforations, slots, or otherwise, for the passage therethrough of oil or other lubricating material, which is supplied in the upper end of the upper shell, C, which is formed in cup shape, as

at C'. The upper lining, E, is extended below the upper shell, C, and has loosely mounted thereon the driving-pulley F, the lower flange, F', of which is made to project farther than 55 the upper flange, in order to maintain a driving-belt in connection therewith, the belt employed, preferably, being a round belt and departing from the machine horizontally.

From the hub of the pulley F there extends 60 inwardly a screw, F², which projects into a slot, D', formed in the spindle D, which spindle rests upon a step, G, arranged in the lower shell, C, which is continued below the pocket B, and interiorly screw-threaded to receive an 65 adjusting-bolt, G', having a hand-wheel set-nut, G², mounted thereon, the bolt itself being operated by a pin or bar, G³, projecting therefrom. The upper end of the lower pocket, B, is also formed in cup shape, as at B', to receive 70 a supply of oil from the lower bearing and such oil as may escape from between the pulley and spindle and lower shell at the point where these last two elements abut against each other. The upper end of the lower lining, E, is re- 75cessed, as at E', so as (in a great measure) to prevent the escape of oil between the lower end of the pulley and that portion of the shell upon which it bears, and so as to guide the oil along the spindle down into the lower bearing. 80

The upper end of the spindle is recessed, as at D², to receive the conical end of the separator-spindle H, whereby motion given to the lower spindle is conveyed to the upper spindle by the friction of the two upon each other. 85

Within the opening formed at the top of the stand is a box, I, which is suspended by means of a rubber washer, I', set in grooves formed in the inner wall of the opening of the stand and in the periphery of the box I. An 90 oil-cup, I², is also formed in the top of the box I. It will be noticed that the box I is not strictly a bearing for the shaft H, but that said shaft is of a materially less diameter than the bore of the box. In other words, I provide 95 this box merely for the purpose of preliminarily supporting or retaining the shaft in a substantially vertical position when at rest, and during the commencement of the rotation thereof when in use, as and for a purpose 100 hereinafter more fully described.

The upper end of the stand A is provided

with a flange or shoulder, A⁵, upon which is mounted the delivery-vessel J of the machine. This vessel consists of a single casting, and may or may not, as desired, be porcelain-lined 5 or otherwise treated to prevent injury to any particular liquids received therein and passing therethrough. In its make-up the delivery-vessel comprises a body portion, J, divided into two annular chambers, J' J², by means of an inwardly and upwardly projecting flange, J³, a high-delivery pipe, J⁴, and a low-delivery pipe, J⁵. The bottom of this vessel is perforated, as at J⁶, for the passage of the shaft H, and is provided with a downwardly-dependent flange, J⁷, adapted to fit upon the head of the stand and rest upon the flange A⁵ thereof, and to be secured in such position by means of a set-screw, J⁸.

K represents the separating-vessel, which 20 embodies one of the important novel features of my invention in that it constitutes in itself a coil having discharge-openings projected toward the center of the vessel, and being adapted to receive liquid directly therein from a receiving-vessel, L, which in this instance is 25 formed as a part of the separating vessel or chamber, or which may be, if desired, formed separately therefrom and set therein, as shown by dotted lines Y, Fig. 1. The separating-vessel consists in this instance of two castings—the one, K', forming the top or cover, and the other, K, forming the bottom, body, or main portion thereof—the former being secured to the latter by means of bolts K², passing 30 through the cover and into apertures K³ formed in the body portion. (See Fig. 4.)

By reference to Fig. 4 it will be seen that the 35 passages formed in the separating-vessel involve the following particulars of disposition: 40 A receiving-branch, M, into which a delivery-pipe, L', from the receiving-vessel L enters. The receiving-branch extends radially to near the circumference of the vessel, where it is curved, as at M', and is continued, so as to conform to the circular shape of the vessel, and nearly completely around the same, where it is again curved, as at M², and directly inwardly, as at M³, and thence downwardly, as at M⁴, and is provided with an outlet, as at M⁵. (See 45 Fig. 1.) This description of the outlines of the passage has reference in part more particularly to its outer walls.

By reference to Fig. 4 it will be seen that the 50 area of the passage just described is enlarged inwardly on inclined (or it may be on curved) lines, so as to form openings M⁶, communicating with the interior depressed neck portion, N, of the vessel. This latter portion is provided at its center with a hub, N', adapted 55 to snugly fit the shaft H. In its bottom and opposite the outlet or discharge orifice M⁵ there is provided a discharge-orifice, N². These outlets or discharges M⁵ N² are so arranged 60 that the former communicates with the upper annular chamber, J', of the delivery-vessel, and the latter with the lower chamber, J², of

said vessel. The discharge-opening M⁵ is represented in Fig. 1 as a plain orifice, the discharging capacity of which may be varied by means of a screw, P, which may be turned to 70 cover more or less of said opening, and thus determine the quantity of liquid that shall pass therethrough.

In Fig. 3 I have illustrated a modification of the means for determining the quantity of 75 fluid which shall pass through the discharge-opening. In this figure the screw P is represented as simply closing a core-hole in the casting K, and the opening M⁵ is screw-threaded for the reception of a screw, Q, which is perforated, as at Q', and adapted to project into the discharge-passage M⁴, more or less in accordance with the capacity of the discharge 80 desired, as it is apparent that the more milk there is discharged the purer the cream will 85 be, and thus I can control the quality of the cream.

From the description above given and the detailed description of the conformation of the 90 passage formed in and constituting the separating-vessel, it will be seen that it is in fact a coil having inwardly-extending branches, the entrance end of the coil being in a plane above the exit end thereof, so that by reason of the configuration of the separating-vessel 95 centrifugal force and the attraction of gravity individually contribute their share toward a perfect separation of liquids of different specific gravities.

In a companion application, No. 193,725, 100 filed March 2, 1886, pending herewith, I have shown, described, and claimed the combination of a coil having inwardly-extending branches with a separating-vessel. In this instance I have constructed a coil which is in 105 itself the separating-vessel. I have also in this instance disclosed other improvements in machines of this class which are adapted to be used in connection with machines embodying a coil and a separating-vessel, as well as in 110 machines embodying a separating-vessel without a coil, and while I do not claim, broadly, in this instance the subject-matter above mentioned as being comprised in my companion application, I do not limit my invention in all 115 respects to a use of the same in a machine in which the separating-vessel is itself a coil.

The operation of my invention as herein shown and described is as follows: By any 120 suitable means motion is given to the spindle D, which is by friction communicated to the spindle H, so as to cause the same and the separating-vessel rigidly mounted thereon to rotate. By any suitable well-known means 125 milk is delivered into the receiving-vessel L, and is conducted by the pipe L' directly into the coil at M, where it is by centrifugal force suspended, as it were, within the coil and within its enlargements leading to the exits M⁶. During the rapid rotation of the separating-vessel the heavier portions of the liquid 130 therein are forced outwardly from the center

of rotation, and the lighter portions are directed inwardly through the openings M^6 , when, by reason of the vertical walls of the neck portion N of the separating vessel, such 5 lighter portions are protected from the influence of centrifugal force while falling by gravity to the bottom, and finally out of the vessel, through the orifice N^2 thereof, and into the lower annular chamber, J^2 , of the delivery- 10 vessel, and finally out of the pipe J^5 thereof. During this operation the heavier portions of the liquid pass through the coil or coil-passage and its downward extension M^4 , and finally out of the separating-chamber, through the 15 discharge-orifice M^5 , and into the upper annular chamber, J' , of the delivery-vessel, and out of its discharge-pipe J^4 . When the machine is first started, the shaft H comes into contact with the box I at various points, and the motion of the separating-chamber is irregular 20 until a certain speed of rotation is attained, when the said shaft runs perfectly free from contact with the box I . The lower section or shaft, D , being arranged concentrically with 25 the upper shaft, it will be seen that the separating-vessel is supported and rotated wholly upon the lower end of the shaft D , and this in turn is wholly supported upon the step G , so that a minimum of friction is secured, and, 30 what is fully as important, the separating-vessel and its shaft are permitted to find their own center of rotation without obstruction from any bearings or boxes in which said shaft rotates.

35 The cover K' , with its receiving-vessel, is so made that it forms the upper wall of the coil-form liquid-passage of the separating-vessel, and when placed in position the delivery-pipe L' of the receiving-vessel passes downwardly 40 and directly into the receiving end of said coil-form liquid-passage. When, however, the receiving-chamber is made separate from the cover K' , it is only necessary to introduce the delivery-pipe of the receiving-chamber 45 into the receiving end of the coil-form liquid-passage at the time of placing the receiving-chamber upon the cover.

Heretofore receiving-vessels have been made for the reception of the drum and with a lateral flange for supporting the same, and with its discharge-pipes depending below and within the area of the flange. By my construction one advantage secured is that the separated liquids may be received in a receptacle or receptacles outside of the frame-work.

Having thus fully described my invention and its operation, what I claim is—

1. In a centrifugal machine, a separating-chamber having a coil-shaped passage provided with outlets disposed toward the center

of rotation of the chamber, substantially as specified.

2. In a centrifugal machine, a separating-chamber having a passage of coil form provided with outlets disposed toward the center 65 of the vessel, and having an inlet to said passage arranged in a plane above the outlet thereof, substantially as specified.

3. In a centrifugal machine, a separating-vessel having a passage of coil form provided 70 with outlets projecting toward and leading into the center of the vessel, which center is depressed below the general plane of the coil and provided with an outlet, substantially as specified.

4. In a centrifugal machine, the combination, with a separating-vessel having a passage of coil form provided with outlets disposed toward the center of the vessel, and having the receiving end of the coil in a plane above 80 the delivery end thereof, of a delivery-vessel having annular chambers arranged one above the other and each provided with a separate discharge-pipe, substantially as specified.

5. The delivery-vessel herein shown and described, consisting of a single casting open at the top for the reception of a separating chamber or bowl of a centrifugal machine, provided with a depending flange at its bottom for connection with a frame or standard, divided into separate annular chambers, each of which is provided with a laterally-extending discharge-pipe and provided with a central opening for the passage of the shaft of the drum, substantially as specified. 95

6. In a centrifugal machine, the combination of a frame or stand having an annular flange at its top, a delivery-vessel having a depending flange adapted to fit the stand, a separating-vessel and its shaft, and a boxing 100 bored larger than the shaft and arranged in the frame, substantially as specified.

7. In a centrifugal machine, a separating-vessel formed with a liquid-passage of coil form, in combination with a cover for the same, 105 and with a receiving-vessel having a delivery-pipe extending into the receiving end of the coil-form passage, substantially as specified.

8. The separating-vessel herein shown and described, consisting of a casting having a coil-form liquid-passage, in combination with a cover provided with an integral receiving-vessel having a discharge-pipe projecting radially therefrom, substantially as specified.

In testimony whereof I affix my signature in 115 presence of two witnesses.

CHARLES A. BACKSTROM.
